UNITED STATES PATENT OFFICE.

HARLAN P. WILDER, OF GARDNER, MASSACHUSETTS.

DESIGN FOR A COLLAR.

SPECIFICATION forming part of Design No. 28,914, dated June 21, 1898.

Application filed May 7, 1897. Serial No. 635,595. Term of patent 14 years.

To all whom it may concern:

Be it known that I, HARLAN P. WILDER, a citizen of the United States, residing at Gardner, in the county of Worcester and State of Massachusetts, have invented and produced 5 a new and original Design for Collars, of which the following is a specification, reference being had to the accompanying drawing, showing a part thereof.

10 In the drawing the figure is a plan view of the collar opened or flattened out.

The leading feature of my design consists of a collar having recesses in the back part thereof, these recesses being open at the bottom and having three sides—namely, a top and two side walls—the top of the recesses being parallel with the top of the collar, while 15 the side walls of the recesses extend downwardly from the ends of the straight upper

wall to the lower edge of the collar, the side walls being slightly curved.

A represents the collar, and B the button-hole at the back thereof.

C and C' are the recesses or cut-away portions extending upward from the lower edge 25 of the collar, leaving the central portion D of the full width of the collar, in which is placed the buttonhole B.

I claim—

The design for a collar herein shown and 30 described.

In testimony whereof I affix my signature in presence of two witnesses.

HARLAN P. WILDER.

Witnesses:

II. M. GATES,
M. C. LYONS.
